UNITED STATES PATENT OFFICE.

EDWIN J. SWIFT, OF DOBBS FERRY, NEW YORK.

CARTON-FILLING DEVICE.

Application filed December 8, 1925. Serial No. 73,984.

This invention relates to carton filling devices and more particularly to a novel and improved means for filling a carton with a plastic or semi-plastic food or composition 5 of matter such as described in my Patent No. 1,587,385.

One of the objects of my invention is to provide a carton filling device in which a container such as a collapsible or substantially rigid carton is plunged into a plastic or semi-plastic mass and completely filled in one 10 operation, said filled carton being inverted and removed from the device whereby it may be closed or sealed.

Another object of my invention is to provide a carton filling device open at its top and bottom to receive either a polygonal or cylindrical carton in an inverted position whereby it may be forced into a plastic or 15 semi-plastic mass completely filling the said carton and then removed from the top of the device to be closed or sealed.

Another object of my invention is to provide a carton filling device of the character 20 of the type above specified, embodying a novel and improved flat, platform which closes the open top of the device in one position and releasable to another position to support the filled container preliminary to 25 its removal and sealing.

With the above objects in view and others which will readily suggest themselves, drawings depicting a preferred form of the invention are annexed hereto wherein—

Fig. 1 is a perspective view, a portion of the bottom being broken away to show the knife edge and bottom support for an inverted container.

Fig. 2 is a similar view showing a cylindrical type carton filling device.

Fig. 3 is a detail showing the guiding means for the sliding platform.

Referring now to the drawings wherein like reference characters designate corresponding parts throughout the several views, 5 designates the front or rear wall and 6 the sides of a polygonal shaped container, open at its top 7 and bottom 8. On the inner surface of the walls and sides, I provide 10 a ledge 9 slightly above the bottom knife edge 10 to support the inverted polygonal container 11 which is inserted within the container with its closure flaps bent back. The height of the said container is slightly 15 greater than the height of the carton, the closed bottom extending to the edge of the

open top for a purpose presently to appear. Rising vertically of the container, I provide a frame consisting of rigid, parallel sides 12, 13, the lower ends 14 of which are 20 bent inwardly flush with the outer walls of the container and permanently secured thereto as by soldering, riveting or an equivalent manner. The portion of the frame above the open top of the container is of a 25 height somewhat greater than the height of the carton so that the latter may be easily and conveniently removed when filled as the entire device is inverted from the position shown by Fig. 1.

The sides of the frame are connected at the top by a cross bar which braces the same, said bar 15 being preferably rigidly attached at its ends in any suitable mechanical manner. Passing through the bar, there is provided a plunger rod 16 which carries a platform or plate 17 at its lower end, said plate being adapted to completely close the open top of the container when the carton is positioned to be filled. The platform or plate 20 also retains the carton in an immovable position when forced into the plastic or semi-plastic mass.

The ends of the platform or plate are provided with pins or lugs 18 bent upwardly 25 and extending slightly beyond the edges thereof being adapted to operate and slide in the inner grooves 19 of the frame above referred to. If so desired the platform or plate may be made integral with a lug or extension to operate in the said guides for the same purpose. An operating handle 20 connected to the upper end of the plunger rod permits the platform to be raised or lowered in the obvious manner.

In the form of the invention shown by Fig. 2, a cylindrical container 21 is shown having a peripheral knife edge 22 and ledge 23 on which the bottom of the inverted carton 24 may be positioned. The top of this type container is also open and the diameter is slightly greater than the diameter of the carton employed. The sides of the frame however are bent slightly outwardly the top edge of the container as indicated by numerical 25 to permit the free outward movement of the carton on the platform. The cylindrical platform or plate 26 operates in the same manner as that shown and described in connection with Fig. 1.

From the above description it will be readily understood that in filling a carton with

a plastic or semi-plastic mass, the carton with its open top is inserted within the container so that it rests on the ledge adjacent the bottom. The plunger rod and its platform or plate are then moved to close the open top of the container to prevent the carton from moving or shifting. When thus positioned and plunged or forced into a plastic or semi-plastic mass, the carton may be filled completely in one operation. After the container is withdrawn from the mass, it is only necessary to invert said container, whereupon the carton, seated on the platform or plate may drop out of the container in its filled condition and removed ready to be sealed.

Having shown and described my invention, what I now claim as new and desire to secure by Letters Patent of the United States is:

20 1. A carton filling device of the class described comprising a container open at its top and bottom for receiving a carton in an inverted position, an open frame attached to and extending above the said container, 25 a slideable plate or platform in said frame constituting a closure for the top of the container in one position and a seat for a filled carton in a second position, said plate or platform being movable toward one end 30 of the frame whereby said filled carton may be removed through the said open top.

2. A carton filling device of the class described comprising a polygonal container open at its top and bottom for receiving a carton in an inverted position, the bottom of the container having a knife edge for penetrating a plastic mass, an open frame attached to the sides of the container and extending above the open top and a plate or 35 platform constituting a seat for a filled container in one position and a closure for the open top of the container in a second position, said plate being movable toward one end of the frame by the weight of a filled 40 container thereon when the device is inverted whereby the filled carton may be removed through the said open top.

3. A carton filling device of the class described comprising a polygonal container open at its top and bottom for receiving a carton in an inverted position, the bottom of the container having a rectangular knife edge for penetrating a plastic mass, a ledge formed on the inner walls of the container 50 adjacent the bottom, a frame attached to the container and extending above the open top and a movable plate or platform operable in the frame from a position closing the top of the container to one end of the open 55 frame, said plate being free to move in the frame by the weight of a filled carton resting thereon when the device is inverted whereby the said filled carton may be removed through the open top.

4. A carton filling device of the class described comprising a container open at its top and bottom for receiving a carton in an inverted position, an open frame connected to the opposite sides of the container and extending considerably above the open top, a 60 freely movable plate or platform and an operating plunger rod therefor movable in said frame from a position closing the said open top to one end of the open frame, said plate being free to move in the frame by the weight of a filled carton resting thereon when the device is inverted whereby the said filled carton may be removed through the open top.

5. A carton filling device of the class described comprising a container open at its top and bottom for receiving a carton in an inverted position, an open frame secured to the opposite sides of the container and extending above the open top, a plate or platform and an operating plunger connected thereto slideable in the frame and constituting a closure for the open top in one of its positions, means for guiding the sides of said plate or platform in the frame, said plate or platform being movable to one end of the frame in another of its positions whereby the filled carton may be removed through the frame as the container is inverted.

6. A carton filling device of the class described comprising a container open at its top and bottom for receiving a carton in an inverted position, an open frame having parallel sides connected to the container and extending considerably above the top thereof, grooves formed in the parallel sides, a top connecting bar between the sides, a flat plate or platform having an operating plunger extending through the connecting bar, an actuating handle for the plunger, means on the ends of the plate or platform operable in the grooves, said plate or plunger being movable to close the open top of the container in one position and constituting a support for a filled carton when being removed in another position.

7. A carton filling device of the class described comprising a container open at its top and bottom having a frame extending 115 above the open top and slideable means operable between the sides of the frame for closing the open top of the container in one position and constituting a support for a filled carton in a second position, said slideable means being free to move by the weight of a filled carton thereon when the device is inverted whereby said filled carton may be removed through the open top of the container.

In testimony whereof I affix my signature.

EDWIN J. SWIFT.
